United States Patent Office

Des. 205,230
Patented July 12, 1966

205,230

GAME BOARD

Leonard B. Neet, Rte. 4, Albany, Oreg.

Filed Sept. 3, 1965, Ser. No. 86,829

Term of patent 14 years

(Cl. D34—5)

Fig. 1.

Fig. 2.

Fig. 3.

Fig. 4.

FIG. 1 is a plan view of the game board, showing my new design;

FIG. 2 is a view in side elevation of the game board of the design;

FIG. 3 is a view in front elevation of the game board of the design; and

FIG. 4 is a view in rear elevation of the game board of the design.

The dominant features of my design reside in the full line portions shown.

I claim:

The ornamental design for a game board, as shown and described.
